BACKING PLATE FOR PULLS

Emil J. Bocade, Wyoming, Mich., assignor to Keeler
Brass Company, Grand Rapids, Mich.

Filed Sept. 29, 1972, Ser. No. 293,441

Term of patent 14 years

Int. Cl. D8—09

U.S. Cl. D8—179

FIG. 1

FIG. 2

FIG. 5

FIG. 4

FIG. 3

FIG. 6

FIG. 1 is a front elevation view of the backing plate for pulls;

FIG. 2 is a bottom, side elevation view of the backing plate of FIG. 1;

FIG. 3 is a side elevation view of the backing plate of FIG. 1;

FIG. 4 is a cross-sectional view of the backing plate taken along plane 4—4 of FIG. 1;

FIG. 5 is a cross-sectional view of the backing plate taken along plane 5—5 of FIG. 1; and

FIG. 6 is a cross-sectional view of the backing plate taken along plane 6—6 of FIG. 1.

I claim:

The ornamental design for a backing plate for pulls, substantially as shown.
